United States Patent Office.

IRA H. STOCKWELL AND LIZZIE C. GOODWIN, OF WORCESTER, MASSACHUSETTS.

Letters Patent No. 80,781, dated August 4, 1868.

IMPROVEMENT IN TATTING-SHUTTLES.

The Schedule referred to in these Letters Patent and making part of the same.

TO ALL WHOM IT MAY CONCERN:

Be it known that we, IRA H. STOCKWELL and LIZZIE C. GOODWIN, of Worcester, in the county of Worcester, and State of Massachusetts, have invented a new and improved Tatting-Shuttle; and we do hereby declare that the following is a full, clear, and exact description thereof, which will enable those skilled in the art to make and use the same, reference being had to the accompanying drawings, forming part of this specification.

This invention relates to the construction of an article called a shuttle, which is extensively used by females in fabricating what is known as "tatting," (a kind of trimming or edging for female under garments.)

And the invention consists in forming the shuttle with a stationary point, and with an elongated stud or stand, as will be hereinafter more fully described.

Figure 1 is a longitudinal section of the shuttle, showing the part on which the point is formed, and also the form and position of the stud, by which the two parts of the shuttle are united.

Figure 2 is an edge view of the shuttle complete.

Similar letters of reference indicate corresponding parts.

The thread of which the tatting is formed is wound on the elongated stud, between the leaves or parts of the shuttle.

These parts are marked A and B.

C is the stud.

Upon the part A there is a point, D, formed, which, in the process of "tatting," is extremely useful in separating the threads of the work.

The stud C is formed of a curved piece of metal, with rounded or semicircular ends, as seen at e, around which the thread to be used in tatting is wound.

This stud or curved piece, C, is soldered or otherwise confined to the parts A and B, as seen in fig. 2.

The leaves or parts A and B are made of any suitable sheet metal, and being thus united form a light and convenient shuttle, and, as combined with the point D, a greatly-improved article for ladies' use is obtained.

Having thus described our invention, we claim as new, and desire to secure by Letters Patent—

As a new article of manufacture, a tatting-shuttle, having one of the ends of one of its sides sharpened to or provided with a point, substantially as and for the purpose specified
